SIDNEY Y. WHITE, OF NEW YORK, N. Y., ASSIGNOR TO EDWARD H. LOFTIN, TRUSTEE

ELECTRON TUBE SYSTEM

Application filed April 18, 1930. Serial No. 445,285.

The present invention relates to improvements in electron tube systems, and more particularly relates to improvements in the structures disclosed and claimed in my co-pending application Serial Number 381,754 filed July 29, 1929.

An object of my invention is the location of a choke coil, such as the field winding of an electrodynamic speaker, within a direct coupled electron tube system so that the coil reacts with a condenser of the system to form a so-called choke-condenser output system, while the coil or field winding is energized in such a manner that no additional current drain is imposed upon the source of energy supply, such as the usual rectifier and filter system used in connection with operation from an alternating current source, over that required for the energization of the tubes of the cascaded system.

Other objects of my invention will become apparent as the following description thereof is developed with reference to the accompanying drawing which diagrammatically illustrates an arrangement of my invention.

In the drawing RT designates a rectifier tube energized from a source of alternating current AC through a power transformer PT. In shunt to the positive terminal P and the negative or grounded terminal G of the rectifier is connected a filter system comprising a filter choke coil FCh and two filter condensers FC₁ and FC₂ connected in the manner shown.

The positive terminal P is connected through the choke coil FCh to the plate electrodes of tubes VT₂ and VT'₂, shown connected in parallel, which tubes have their filaments energized from a common heating current transformer HT₂. These tubes VT₂ and VT'₂ may be replaced by a single tube having the characteristics of these parallel-connected tubes. The secondary of transformer HT₂ is provided with the usual center-tap potentiometer CT₂, which potentiometer is connected through the coil SFC, shown as the field coil of the well-known electrodynamic speaker, and a resistance R to the negative terminal G of the rectifier. The cathode of tube VT₁, shown as the

conventional screen-grid type, is connected to the terminal G through a stabilizing resistance SR, the cathode of this tube being heated by means of current supplied to the heater element thereof through a heating current transformer HT₁ the secondary of which is connected to the point A on the resistance R in the manner shown. The screen-grid of tube VT₁ is connected to a point B of proper potential on the resistance R. The grid of tube VT₁ is returned to the point A on the resistance R through a signal input system IS, the difference of potential between the cathode of tube VT₁ and the point A functioning to stabilize the system in the manner described in detail in my copending application hereinbefore referred to. Between the cathode of tube VT₁ and the adjustable point D on the resistance R I have connected a so-called "hum-bucking" condenser HBC, the function of which is likewise described in detail in my copending application hereinbefore referred to.

Between the plate electrodes of tubes VT₂ and VT'₂ and the filaments thereof I have connected a pair of high resistances R' and R'' carrying current only of the order of the space current of tube VT₁. I have directly connected the plate of tube VT₁ to the grids of tubes VT₂ and VT'₂, and have connected all these electrodes to the point between the resistances R' and R'' by way of resistance CR.

Between the plates of tubes VT₂ and VT'₂ and the filament potentiometer CT₂, thereof I have series connected a signal current condenser C₂ and the primary of an output or coupling transformer OT, the secondary of which is connected to the voice or signal current coil VC of the loud speaker LS.

The operation of the system is as follows: The sum of the space current flowing through the tubes VT₂ and VT'₂ energizes the speaker field coil SFC and develops a potential between the terminals CT₂ and G. Current flowing through the tube VT₁ from the potentiometer R', R'' produces differences of potential in the resistances CR and SR, the potential developed across the resistance CR determining the proper grid bias for the

tubes VT_2 and VT'_2 . The proper bias for the entire system is determined by the difference between the potentials of the cathode of tube VT_1 due to space current flow thereof 5 through the resistance SR and of the point A on the resistance R due to the space current of tubes VT_2 and VT'_2 flowing therethrough, all as more specifically stated in my heretofore mentioned co-pending application.

10 When signal current potentials are impressed through the input system, there are developed amplified signal current potentials across the resistance CR which cause signal current variations in the space current flow through the tubes VT_2 and VT'_2 .

15 Tracing the plate-cathode path of the tubes VT_2 and VT'_2 it is seen that the speaker field coil SFC is in series therein, and therefore energized by the combined current of these 20 tubes, and, in addition, acts as an effective signal current choke coil forcing the signal fluctuations to flow through the condenser C_2 and the output transformer OT . Hum within the system is controlled through the 25 adjustment of the point D along the resistance R .

30 While I have described my invention as embodied in a specific apparatus, it is to be understood that this structure is exemplary only and various modifications thereof may be 35 made without departing from the spirit of my invention as defined in the claims appended hereto.

35 Having thus described my invention, what I claim is:

1. In an electron tube system, the combination of a source of unidirectional cur-

rent, an indicator having a field coil and an input impedance, an output tube the plate of which is directly connected to the positive terminal of said source, the cathode of said tube being connected to the negative terminal of said source by way of said field coil, and a coupling between the plate and cathode of said tube including in series a condenser and said input impedance of the indicator, whereby said indicator is energized 70 at least substantially with discharge current from said output tube.

2. In a direct-coupled tube system, the combination of a source of unidirectional current, an indicator having a field coil and an input impedance, a plurality of tube stages direct-coupled in cascade relation including an output stage the anode side of which is directly connected to the positive terminal of said source and the cathode side of which is connected to the negative terminal of said source by way of said field coil and a potential developing element in series therewith, a coupling between the anode and cathode side of said output stage including in series a condenser and said input impedance of the indicator, and means including said potential developing means for energizing electrodes of said tube stages whereby the current drain on said source is substantially confined to the greater one of the currents required for the space discharge of said output stage and for the energization of said field coil.

100 In testimony whereof I affix my signature.

SIDNEY Y. WHITE.
